Attorney

UNITED STATES PATENT OFFICE

MAX WEBER, OF EUPEN, BELGIUM

DEVICE FOR PREVENTING DOUBLES IN SPINNING MACHINES

Application filed October 27, 1927, Serial No. 229,237, and in Germany November 30, 1926.

There have already been proposed various devices for preventing the formation of doubles in spinning and twisting machines. These known devices consist either of fixed sheet metal plates arranged between the threads and provided with catching slots or of swinging or revolving hooks. While comparatively good results may be obtained with the said slotted fixed plates, same possess the serious drawback that, in order to render them effective throughout the entire length on which the spinning or twisting of the yarn takes place, they have to be made of a length corresponding to the distance between the drawing rollers and the bobbins or spindles. Stationary plates of such a length form large surfaces on which spinning fly and dust may easily deposit and accumulate. In case a draught of air passes through the machine or broken threads impinge on the plates, the fly and dust thereon will come into contact with and contaminate the threads. Besides, the survey of the totality of threads is greatly impaired by the said plates because they are stationary and of large dimensions. The known swinging or revolving hooks have the disadvantage that they are only operative on a definite portion of the space between the drawing rollers and bobbins, namely between the front drawing roller and the thread guide or between the latter and the bobbins. These hooks therefore cannot prevent the formation of doubles on the other portion of the said space. Moreover, the action of these swinging or revolving hooks is rather imperfect in as much as they are not of such a shape as to allow them to seize and hold broken ends immediately. They act only by pressure on one of two ends which are already twisting in with each other and cause a breaking down of the doubles by the tension to which the ends are thus subjected. Now, worsted yarn is for instance very elastic and a worsted end seized by such a swinging hook would be several times taken along by the same up and down and therefore go on for some time twisting in with an adjacent end before it breaks under the tension. The known swinging hooks are therefore en-

tirely unsuitable for use on worsted spinning machines.

The present invention has for its object to provide a device for preventing the formation of doubles in spinning machines which does not possess the drawbacks of the known devices. The device consists likewise of sheet metal plates provided with incisions for catching the broken ends and arranged between the threads. According to the invention, these plates are mounted substantially in the middle between the front drawing roller and the top ends of the bobbins for vertical swinging motion so that, in operation, they will move throughout the entire height of the space between the front drawing roller and the bobbins. These oscillatory plates will securely prevent any formation of doubles both above and below the thread guides. As the plates are mounted for swinging motion at the centre of the distance through which the threads being spun pass, they need only have half the length of the known stationary plates. The surface of the plates on which spinning fly and dust may deposit is therefore essentially reduced. Besides, an accumulation of fly and dust cannot occur at all because of the constant up and down movement of the plates. The swinging plates also do not interfere with the survey of the totality of threads in an appreciable degree, since the whole row of threads is fully open to inspection alternately below and above the axis of rotation of the plates according to whether the plates are at the upper or lower end of their stroke.

The new device is more particularly adapted for use in worsted ring spinning machines.

An embodiment of the subject-matter of the invention is illustrated, by way of example, in the accompanying drawing, in which: Fig. 1 is a diagrammatic cross-section of a portion of a ring spinning machine with the device according to the invention applied thereto,

Fig. 2 is a diagrammatic front elevation of some threads with plates to prevent doubles arranged between the threads.

The drawing only shows those parts of a ring spinning machine which are necessary

for allowing the invention to be understood.

a are the drawing rollers, *b* are the bobbins and *c* are the guide wires through which the threads *F* being spun pass on their way from the drawing rollers to the bobbins. Arranged 5 intermediate adjacent threads are sheet metal plates *d* provided with incisions *f* designed to catch broken ends of yarn.

In the embodiment illustrated, the plates *d* are shown to be fastened on a common horizontal rock shaft *g* which is arranged substantially in the middle between the front drawing roller and the top ends of the bobbins *b*. This shaft *g* is designed to have partial rotations in opposite directions imparted to it by any suitable means well-known in the art. Owing to these rocking motions of the shaft *g* the plates *d* are alternately moved up and down on the path A—B so that they 15 will securely catch broken ends or break down 20 doubles which are being formed.

In operation, the plates *d* swing up and down clear of the threads *F*. If an end of 25 yarn breaks, this broken end is either immediately caught by one of the adjacent swinging plates *d* and thus prevented from coming into contact with another end, or if it reaches 30 one of the adjacent ends and commences to twist in with the same it will even the more securely be seized by the swinging plates, because the broken end then extends transversely of the path of movement of the plates. In 35 the latter case the formation of doubles will therefore be stopped already at the beginning. In this case, especially in the formation of doubles above the guide wires of ring spinning machines, the plates do not only seize the broken end but they also seize and break down the end with which the broken 40 one is twisting in. This has the advantage of allowing the spinner when piecing-up the ends to make out the short piece of double formed and remove it.

Fig. 2 illustrates how a broken end of yarn 45 has flown to an adjacent end and is twisting in with the same. It will be understood that in the upward movement of the plate *d* lying below the transversely extending broken end this plate will catch the double in formation 50 in one of its incisions and break it down.

Having thus described my invention, what I claim as new and desire to secure by Letters Patent is:—

55 In combination with a spinning machine, means for preventing the formation of doubles comprising a horizontal rock shaft arranged substantially in the middle between the front drawing roller and the top ends of 60 the bobbins, sheet metal plates with slotted edges fastened on the said shaft so as to extend between the threads parallel thereof and adapted to be swung up and down by the shaft, these plates being of such a shape and 65 size that when operated they will move from

end to end of the space between the front drawing roller and the bobbins.

In testimony whereof I have signed my name to this specification.
